Primary Examiner—Ian Simmons*Assistant Examiner*—Charles D Hanson(74) *Attorney, Agent, or Firm*—Cooper & Dunham LLP(57) **CLAIM**

The ornamental design for a cellphone plug adapter, as shown and described.

DESCRIPTION

FIG. 1 is a perspective view thereof;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is the other side view thereof.

The broken lines in FIGS. 1, 2, and 3 are for illustrative purposes and form no part of the claimed design.
